**DEVICE FOR INTRODUCING WASHING AGENTS INTO
THE VESSEL CONTAINING SUDS OF A FULLY
AUTOMATIC WASHING MACHINE**

DISCLOSURE OF THE INVENTION

The invention has reference to a fully automatically controlled washing machine having one or more than one container for the washing agent, and shutoff valves for water through which, firstly water and, after an adjustable level has been reached, the washing agent is, or agents are, passed into the vessel containing the suds, hereinafter called the "suds tank".

Hitherto two magnetic valves have been used in such devices, which at one time admit to the suds tank plain water and, at another time, water passed through the container for the washing agent. The disadvantage of such an arrangement is that two magnetic valves are required. In addition to the more complicated construction and to the larger space required, the arrangement has the further drawback that it requires the control of the two magnetic valves in accurately timed succession.

The object of the present invention is to eliminate these drawbacks, and to pass plain water, as well as water flowing through one or more than one container for washing agent through a single magnetic valve, e.g. for both the prewashing and the main washing periods.

According to the invention this object is achieved in that a water switch capable of being adjusted is arranged in such a manner that it admits the incoming water selectively, either immediately into the suds tank or container or via a washing agent container. Obviously, it is also possible, according to the invention, for the water switch to pass the admitted plain water in the first place through one container, which accommodates a prewashing agent and which, after the end of the prewashing phase effects a switchover in order then to admit the washing water through the container for a washing agent intended for use in the main washing process. It is also possible to effect one or more than one additional switchover for the purpose of allowing the water to flow through other containers, e.g. containers for use during rinsing, or during starching or in other processes.

An advantageous arrangement consists in that the water switch is designed as a flap acting as a valve arranged in the water inlet and adapted, at one time, to stop the admission of water to the container for the washing agent and at another time, to stop the admission of water to the suds tank of the machine. This arrangement results in a particular simplification if the valve proper is designed at the same time as the water switch.

Furthermore, it is of advantage to control the operation of the valve flap thermostatically, e.g., by means of a bimetal strip or spring. In such an arrangement it is possible to control the operation of the flap with the bimetal strip either independently of the water temperature, or to utilize the time required for the heating of the bimetal strip as a control factor for the flap operation.

There is the alternative possibility of controlling the displacement of the valve flap pneumatically, e.g., by means of a heating coil arranged within a bellows which is operatively connected with the flap, the heating of the air enclosed within the bellows, by means of the heating coil, effecting a motion of the bellows together with the flap. In this embodiment of the invention both the heating and time are used as controlling factors since the change of the temperature is effected within a period of time and is, therefore, dependent on the time.

Moreover, it is of advantage to design the bellows which encloses the air and the heating coil, as a shutoff means which arrangement results in a further simplification of the construction.

Further, it is of advantage to arrange the heating coil in series with the solenoid coil of the magnetic valve, the latter coil being arranged within the water inlet which leads to the valve

flap. This arrangement ensures that the magnetic valve arranged in series with the valve flap is operated whenever the flap is actuated, without depending on a program control. It is furthermore of advantage for the valve flap, if it is arranged symmetrically within the water inlet, to be subjected to advance control either thermostatically, or pneumatically or electromagnetically, in one direction or in the opposite direction, and for the pressure head to produce the control movement and to provide the shutoff pressure. Thus the pressure head is used in this arrangement as the effective control factor.

It is also within the ambit of the invention to provide a plurality of water switches in the inlets to the diverse washing agent containers.

Thus, in all embodiments of the invention, a constructional simplification is achieved by the use of a single magnetic valve only. This simplification can even be carried further by providing the magnetic valve with the valve flap adapted to act as a water switch.

As to the control of the magnetic valve, there are many possibilities, viz., control in dependence on the flux of time, in dependence on temperature or in dependence on the pressure head, it being obviously also possible to utilize these controlling factors in any optional combination.

The operation of the valve flap resembles that of a switching contact as it directs the inflowing water either in one direction or in another, it being obviously possible to arrange instead of one admission and two discharge paths, for instance, one admission and more than two discharge paths.

The invention also renders it possible to associate several admission paths with a single discharge path, or to associate a number of admission paths with a multitude of discharge paths.

obviously, it is also possible to effect the control in dependence on the liquid level within the suds tank by effecting the switchover either in dependence on the time when the magnetic valve opens and allows water to flow into the suds tank or vessel, or to effect the switchover of the valve flap by means of a level regulator. With this last-mentioned arrangement the effect is obtained that, particularly during the admission of the principal washing agent, a certain quantity of water is already admitted to the suds tank and is thus more evenly distributed therein than if it were admitted to the empty suds tank in excessive concentration and were then to remain within the sump of the suds tank without participating in the washing action proper.

If the movable end of a valve flap acting as a shutoff means, is so placed into the stream of water that it is retained in that position by the passing water, then a minor deflection to one side or to the other is sufficient for effecting a rapid and sudden deflection of the flap in one direction or in the opposite direction. Very little energy is then required for displacing the valve or shutoff flap, from its symmetrical intermediate position.

Finally, it is possible to use a cascade arrangement if the admission of water is to be effected via a number of water switches.

In order to more particularly describe the invention reference is made to the accompanying drawing which illustrates the invention by way of example only, and wherein:

FIG. 1 shows the conventional method and the arrangement used for introducing washing agent into the washing suds tank, respectively;

FIG. 2 shows diagrammatically the use of a water switch for carrying out such introduction;

FIG. 3 illustrates a thermostatically controlled water switch;

FIG. 4 shows a pneumatically controlled water switch;

FIG. 5 illustrates an expandible bellows which at the same time acts as a shutoff means; and

FIG. 6 illustrates, in principle, the possibility of displacing the valve flap by advance control.

In FIG. 1 the direction of the arrow 1 indicates the admission of water into a distributor socket 2. From the socket 2 the

water is branched off in the direction of the arrow 3 to a magnetic valve 4, and in the direction of the arrow 5 to a magnetic valve 6. From the magnetic valve 4 the water then enters the washing vessel or tank 8, e.g. via a container 7 filled with softening washing agent. From the magnetic valve 6, on the other hand, the water is fed likewise into the suds tank 8 via an additional container 9, which, for instance, may be filled with the washing agent proper.

It will be understood that, whenever the water entering the suds tank 8 in the direction of the arrow 1 is passed in the first place through the containers 7 and 9 for the washing agents, such a strong concentration of washing agent occurs in the lowermost part of the suds tank, that during the immediately following washing phase there is no certainty of a full utilization of the suds, i.e., of the washing agent having been distributed uniformly within the suds.

In fig. 2 in which identical reference numerals denote the same parts as in FIG. 1, an embodiment is shown which includes a water switch 10. This water switch allows the admission of water either in the direction of the arrow 11 immediately to the suds tank 8 or, after adjustment of the water switch in the direction of arrow 12, to the container 7 for washing agent. If—as in FIG. 1—there is provided an additional container 9 for washing agent, then the water switch will switch over after a further influx to the said container 9, after the container 7 has been emptied of washing agent.

The further FIGS. of the drawing illustrate water switches which in each case distribute the incoming water from one inlet to two discharges. There could be provided, of course, an additional water switch in one discharge or in the other whereby water could be admitted to an optional number of containers for washing agent through water switches arranged in series.

In the arrangement according to FIG. 3, the water entering through the inlet 13 in the direction of the arrow 1 is passed first in the direction of the arrow 14 immediately into the tank or vessel which contains the suds. The water switch 10 is provided with a valve flap 15 which in the position shown in full lines in the FIG., engages the valve seat 16 and thereby prevents the discharge through the container 7 for washing agent (not shown) in the direction of the arrow 17. If the bimetal strip 18 which is shown in dotted lines, is heated by the heating coil 19, which is shown only diagrammatically, then it causes the flap 15 to be moved in the direction of the arrow 20 until said flap reaches the position shown in dotted lines at 21. In this position of the flap the water admitted through the inlet enters the container for the washing agent in the direction of the arrow 17. If the magnetic valve 4 arranged in front of the inlet 13 is switched off, then the heating coil 19 is likewise deenergized and the flap 15 is made to return again into the position shown in full lines in FIG. 3.

In the embodiment according to FIG. 4 the valve flap 15 is operated pneumatically since the heating coil 19 is arranged within a bellows 23. The bellows is filled with air and, if the coil 19 is heated, it causes the air surrounding same to expand so that the flap 15 is moved by the bellows through an actuating rod 24 into the dotted lines position 21. The effect is then the same as that described with reference to FIG. 3.

The water switch 10 shown in FIG. 5 makes use of almost the same principle. In this case, however, a bellows 25 is provided which at the same time acts as a shutoff means for the discharge of water in the direction of the arrow 14. If after heating the wire of the coil 19, and owing to the expansion of the air enclosed within said bellows, the body of the latter assumes the position shown in dotted lines at 26, a spring-loaded throttle flap 27 is made to open only when the bellows 25

prevents the direct water flow in the direction of the arrow 14 when said bellows are in the dotted lines position 26. The pressure exerted upon the throttle flap 27 is then considerably increased as the escape in the direction of the arrow 14 is then blocked, so that the flap 27 is made to open thereby causing the water to flow in the direction of the arrow 17 and to wash the washing agent into the suds tank.

FIG. 6 shows diagrammatically that it is possible to arrange the flap 15 in such manner that it assumes the symmetrical position shown in full lines within the water admission 13, so that even a small deflection in the direction of the arrows 28 and 29 is sufficient for removing the flap from the symmetrical position by a change of the pressure head acting on the frontal face of the flap. By this action either the discharge in the direction of the arrow 14 or that in the direction of the arrow 17 is prevented.

I desire to be understood that the invention as hereinbefore described is capable of modification in various ways within the scope of the appended claims, and that it is applicable not only to washing machines for laundry purposes, but also to other washing machines, e.g., dishwashers.

I claim:

1. An automatically controlled washing machine comprising main water supply conduit, a washing tank, at least one container for a washing medium, said at least one container having its outlet opening connected to said washing tank first and second branch conduits connected to said main water supply conduit, the region of connection thereof forming a common chamber, said first branch conduit having its outlet into said washing tank, said second branch conduit having its outlet into said washing machine container, an electromagnetically controlled valve positioned within said main water supply conduit, a water switch positioned within said common chamber, said water switch being adapted to assume a first position wherein the flow of water through said first branch conduit is blocked and water is permitted to flow through said second branch conduit into said washing medium container and to assume a second position wherein the flow of water through said second branch conduit is blocked and water is permitted to flow through said first branch conduit into said washing tank and control means for operating said switch between said first and second positions.

2. A washing machine as claimed in claim 1 wherein said water switch comprises a valve flap positioned in said chamber, the flap effecting in alternation the shutoff of water flow to said first and second branch conduits respectively.

3. A washing machine as claimed in claim 2 wherein said control means includes a heating coil and operation of said flap is effected thermostatically.

4. A washing machine as claimed in claim 3 wherein said control means further includes a bimetal spring.

5. A washing machine as claimed in claim 2 wherein said control means effects displacement of the valve flap pneumatically.

6. A washing machine as claimed in claim 5 wherein said pneumatic control means includes a heating coil arranged within a bellows connected with the valve flap, the displacement of the bellows and of the valve flap being effected by the heating of the air enclosed within the said bellows.

7. A washing machine as claimed in claim 6 in which said bellows with air and a heating coil enclosed therein is designed as a shutoff means.

8. A washing machine as claimed in claim 7 wherein the heating coil is arranged in series with the solenoid coil of said electromagnetically controlled valve positioned within said main water supply conduit.
